DAVID L. LINDQUIST, OF HARTSDALE, NEW YORK, ASSIGNOR TO OTIS ELEVATOR COMPANY, OF JERSEY CITY, NEW JERSEY, A CORPORATION OF NEW JERSEY.

SPRING CABLE HITCH.

1,418,089.

Specification of Letters Patent. Patented May 30, 1922.

Application filed June 18, 1919. Serial No. 305,142.

To all whom it may concern:

Be it known that I, DAVID L. LINDQUIST, a subject of the King of Sweden, residing in Hartsdale, in the county of Westchester and 5 State of New York, have invented a new and useful Improvement in Spring Cable Hitches, of which the following is a specification.

This invention relates to improvements for 10 attaching the ends of the leads of the several hoisting ropes of the elevator car and the counterweight, in a single wrap traction elevator machine, particularly of high rise, in which it is desirable or necessary to equalize 15 the effective length of the different ropes, which will vary due to slight imperfections in the grooves of the driving sheave, deviation in the true alignment of the ropes and the grooves with each other or variations or 20 inequalities in the size of the ropes; more particularly stated, the objects of the improvements are to provide means first for equalizing the effective length of the ropes between the driving sheave and the car and 25 counterweight, which shall operate automatically to equalize the effective length of the ropes. Second: to neutralize the twisting and to minimize the creeping of the ropes; third: to minimize the wear of the 30 ropes and the driving sheave. One of the improvements consists in introducing a coiled metallic spring or other mere equivalent resilient element at the end of the leads of the rope where they are attached to the car 35 and counterweight, the ropes being passed in a single wrap or half turn around the driving sheave, and the car and counterweight suspended from the ends of the leads of the ropes.

40 As has already been stated in effect, in a traction elevator machine, the car is usually hung substantially from one end of the hoisting rope and the counterweight for the car from the other end; and the transmission 45 working parts are reduced to the fewest and simplest parts. They comprise essentially a hoisting motor and a traction driving sheave with grooves in its face in which lay the hoisting ropes for the car and counterweight, passed over the sheave and laid 50 in the grooves, and the ends of the leads of the ropes are made fast to the car and the counterweight or may be passed under an idler sheave on the car and counterweight 55 and the ends of the leads made fast to the

structure supporting the hoisting motor; in some installations, a deflecting sheave may be added to deflect the leads from the driving sheave to the car and counterweight.

Heretofore, in actual service conditions of 60 the elevator, it has been the practice to wrap the hoisting ropes a second time or with two half turns around the hoisting sheave and the deflecting sheave, thereby giving 65 two half wraps on the hoisting sheave, which plan provides the necessary traction between the sheave and rope. In that practice the grooves in the sheaves are usually round, and the rope lays on the bottom of the groove, substantially without any binding 70 between the grooves and the rope. The plan is found to be adequate for all rated loads of the car in the service conditions of the elevator. It is the custom to provide 75 several hoisting ropes, and in the arrangement of two half turns or wraps of the ropes around the sheave, it is not necessary in the operation of the elevator to equalize the strains among the different hoisting ropes 80 beyond the usual shop practice of forming the grooves as perfectly as might be in the work of making them, selecting ropes of the same diameter and arranging the leads to be all of equal length or as nearly so as practicable, aligning the ropes and the grooves 85 with each other as well as can be done in the work of erecting and installing the elevator, and attaching each rope to the car with a swivel rope hitch, which allows a gradual 90 creeping of the rope and minimizes any excessive twisting strain therein and relieves the rope of the bending strains at its junction with the hitch, principally caused by vibration of the rope.

It was known, however, that the hoisting 95 rope might be passed around the hoisting sheave merely in a single half turn or wrap, which would give only a half turn of contact between the hoisting sheave and the rope, and yet sufficient tractive effect be secured 100 between the sheave and rope for all the rated duties of the elevator in service conditions, particularly if a groove of special form was provided to bind the rope. In installations of traction elevators, there may be as many 105 as two, four or six ropes or even a larger number of them; in ordinary conditions, the machine is usually provided with six ropes, of soft steel material. In actual service of 110 the elevator in which the rope has double

or two half wraps around the hoisting sheave, the wear of the sheave and ropes due to the action between them, is not of sufficient consequence to make it desirable 5 or necessary to devise any special means to reduce or minimize the wear; but in an elevator with only a single or half wrap around the hoisting sheave, with special form of groove to bind the ropes, there is apt to be 10 extra wear between the groove and the rope; this is particularly true of traction machines for high rise, and consequent long length of rope; and therefore, it is desirable, if not essential, to reduce the wear. It is found 15 that wear can be reduced by equalizing the effective length of the different leads of the ropes between the sheave and car and sheave and counterweight, which length will vary, due to slight inaccuracies in the grooves and 20 the size of the ropes, and lack of true alignment of grooves and ropes. Also that wear can be reduced by neutralizing the twisting of the ropes at their respective ends and by so doing prevent those sections of 25 the ropes, which are engaged with the grooves of the driving sheave, from twisting and creeping.

It has been found that one of the simplest means to obtain the above mentioned reduction of wear is to introduce metallic spiral springs on the thimble-rods of the hitch for 30 the ropes at the end of the leads of the ropes between the sheave and the car and the sheave and counterweight. Springs of proper strength are selected to suit the load 35 capacity or duty of the elevator and of sufficient elasticity to suit the height of rise or travel of the car and counterweight or the length of the rope. 40 In addition to metallic spring equalizers between the sheave, car and counterweight, it is also desirable, if not essential, as a matter of good practice to arrange the 45 hitches for the leads of the ropes on both car and counterweight so that all the leads will be of equal length or as nearly so as may be possible. In the case of the car, a single swivel hitch for all of the ropes is 50 provided and secured to the car frame, which hitch can be readily turned to suit all of the leads of the ropes. It consists of a cast 55 steel block cored with openings for all of the leads, and held in place in the head of the car frame by means of plates which permit the block to be turned or adjusted to the position of the rope leads relatively to the grooves in the sheave. Owing to lack of space that arrangement is, generally speaking, not possible on the counterweight; 60 but on the other hand, it is not advisable to core specially the top weight of the counterweight for each job; therefore, it has been arranged to cast the top weight of certain widths of counterweights with two different 65 corings and by the use of the one best suit-

ed to the layout, a minimum length of the leads of the ropes can be obtained between the driving sheave and counterweight.

These objects of equalizing the effective length of the leads of the hoisting ropes and 70 reducing wear of the grooves and ropes, are attained by the mechanism shown in the accompanying drawings, in which—

Figure 1 is a double perspective view of a single wrap traction elevator machine, containing the means for equalizing the effective length of the hoisting ropes between the hoisting sheave, the car and the counterweight. 75

Figure 2 is a plan view of the rope hitch 80 secured on the car frame.

Figure 3 is a view taken on line *a—b*, Figure 2, of the rope hitch on the car frame, spring equalizers and thimble-rods, the 85 spring equalizers being shown on the rods.

Figures 4, 5 and 6 are views of cored top weights for the counterweight, showing different plans of coring the top weights to obtain minimum length of leads of the ropes. 90

Figure 7 is a plan view of a car, the driving sheave, and a counterweight, indicating the relative direction that the leads of the ropes between the sheave and counterweight will take when in position. 95

Similar numerals refer to similar parts throughout the several views.

In the drawing, Figure 1, the driving motor, A, and the driving sheave, B, are shown placed overhead or above the car, C, with the hoisting ropes, R, laid in the 100 grooves, *b*, of the sheave, B, in a single wrap of the ropes, R, with the car, C, hung from the end of the leads of the ropes between the sheave and car, and the counterweight, cwt., suspended from the end of the leads 105 of the ropes between the sheave and counterweight.

In order to couple the car and counterweight to the ropes, the ends of the leads are made fast to thimble-rods, 1, which, in the 110 case of the car, are passed freely through holes, 2, in a circular plate, 3, the holes being of sufficiently larger size than the rods to allow the rods to be freely moved circumferentially in the holes to adapt their position 115 circumferentially to any creeping or twisting of the ropes, and longitudinally to allow the rods to be moved by the ropes and spring equalizer, but, in addition to the clearance already spoken of between the holes and rods, 120 the holes are made sufficiently larger than the rods to allow the rods to be wobbled in the holes to enable the rods to maintain their axial alignment with the ropes in case the latter are deflected or vibrated in the operation of the elevator. In the drawing, Figures 2 and 3, the clearance between the rods and the swivel plate is clearly shown. Sleeved on the free ends of the rods passed through the holes in the plate, are washers, 130

4, having on one side a shoulder, entered into the holes in the plate, as shown in Figure 3, and flat on the other side. The shoulder of the washer serves to center the rods in the 5 holes in the plate. Next to the flat side of the washers are metallic spiral or coiled springs, 5, placed on the free end of the rods, and held thereon by nuts, 6, threaded onto the rods. The swivel plate, 3, is mounted on 10 the top of the car frame, as has been stated. In the arrangement shown in the drawing, the usual two cross beams, 7, of the car frame are indicated; on the top of which and spanning them, is the circular plate, 3, which is 15 secured to the beams by plates, 8, which are fast to the beams. The sides of the free ends of the plates, 8, next to the swivel plate, are notched or formed substantially to constitute hooks which engage the swivel plate, 20 and secure it to the beams, but allow the plate to be turned freely about its axis in its place on the beams. The purpose of allowing the plate to swivel or be turned is to permit it to be turned to line the corings 25 with the grooves in order to obtain a minimum length of leads between the sheave and car, but also to allow free rotation of the leads of the ropes regarded as a whole, and thus avoid any resistance to the twisting 30 and untwisting of the ropes regarded as a whole in the operation of the elevator. As has been explained, such a form of swivel plate can be adjusted practically to suit any and all of the leads of the ropes between the 35 car and sheave. The idea of having a single swivel plate, with corings for all of the ropes instead of a single fixed plate, has been found in practice to be virtually necessary in order to obtain the objects and effects already described, and is looked upon as very important 40 feature.

As indicated in the drawing, the holes in the swivel plate and top weight of the counterweight for the thimble-rods are shown 45 staggered, preferably. As has been already explained, it is not possible, generally speaking, owing to lack of space, to arrange such a swivel plate on the counterweight, nor advisable to core specially the top weight of 50 the counterweight for each elevator. It is planned therefore, to cast top weights of certain widths of counterweights with two 55 different corings for the thimble-rods, one top weight having one set of corings and another top weight a different set of corings, and by selecting and using a top weight best suited to the layout of the particular elevator, to obtain a minimum length of leads of ropes between the driving sheave and the 60 counterweight.

In the drawing, the Figures 4 to 6 indicate the top weights for the counterweights for leads of two, three, four, five and six 65 ropes. It will be observed that the holes or corings, 9, in the top weights are staggered,

and in Figures 5 and 6 are moreover set at an angle to a vertical plane on a line drawn through the major center of the weight. In addition to that plan of securing various angles of leads of ropes with minimum 70 length of leads with the weight top-side up, any of the weights may be turned top-side down, and thereby another angle of lead be secured, and a minimum lead obtained. In Figure 7 what the relative direction of 75 the leads between the sheave and counterweight would be are indicated by the relation between the sheave and top weight, showing how a minimum length of all of the leads is obtained between the sheave and 80 counterweight.

Having described my invention, what I desire to claim herein as new and secure by Letters Patent is:

1. In an elevator, the combination of a 85 grooved driving sheave, hoisting ropes in the grooves, a car and a counterweight, hung from the opposite ends of the ropes, and springs between the sheave and the ends of the ropes and the car and the counterweight, 90 the springs serving to equalize the effective length of the ropes.

2. In a traction elevator, the combination of a grooved driving sheave, the hoisting ropes in the grooves in the sheave, the car 95 and counterweight, the car hung from the leads of one end of the ropes, and the counterweight from the leads of the other end of the ropes, metallic springs at the end of each lead of each rope, between the driving sheave 100 and the car and counterweight, whereby the effective length of the ropes between the sheave and car and counterweight is equalized and the wear between the grooves and ropes reduced or minimized. 105

3. In a single wrap traction elevator machine, a grooved driving sheave, hoisting ropes in a single wrap in the grooves, a car and a cored counterweight, hung from the opposite ends of the ropes, thimble-rods for 110 the ropes, fastened to each end of each rope, a multi-cored swivel plate secured to the car, and the free end of the rods passed through the corings on the plate and counterweight, springs and fastening means on the free end 115 of the rods, the fastening means serving to hold the springs between them and the swivel plate and counterweight, whereby the effective length of the leads of the hoisting ropes is equalized. 120

4. In a traction elevator, the combination of a grooved driving sheave, the hoisting ropes in the grooves, the car and counterweight hung from the ends of the ropes, 125 springs at the ends of the ropes at the top of the car between the car and driving sheave and springs at the ends of the ropes at the top of the counterweight between the driving sheave and the counterweight, whereby the effective length of the hoisting ropes is 130

equalized between the sheave, the car and counterweight.

5. In a traction elevator, the combination of a grooved driving sheave, hoisting ropes for the car and counterweight in the grooves, the car and counterweight, hung from the ropes, and a multi-cored swivel plate, hooks securing the swivel plate to the car, and permitting rotation of the plate, the top weight 10 of the counterweight being also multi-cored, rods in the cores in the plate and top weight of the counterweight, with their free ends threaded and projected below the plate and counterweight, one end of the rods secured 15 to the ropes, and springs on the free ends of the rods beneath the plates and counterweight, and nuts beneath the springs threaded on the end of the rods, whereby the effective length of the leads of the ropes is 20 equalized.

6. In a single-wrap traction elevator, the combination of the grooved driving sheave, the hoisting ropes in the grooves, the car and counterweight, thimble-rods fast to the ends 25 of the ropes, a swivel hitch plate secured to the car, and having holes to receive the rods, the holes being of sufficient size to allow the rods to be freely moved therein from side to side, collars beneath the plate and sleeved 30 on the rods and entering the holes in the plate to center the rods therein, and springs beneath the collars and sleeved on the rods, and means to hold the springs in place, whereby there is a flexible attachment of the 35 end of the ropes to the car, and any tendency of the ropes to break off close to their point of attachment by reason of the effect of vibration is avoided.

7. In a traction elevator, a grooved driving sheave, hoisting ropes in the grooves, 40 thimble-rods on the ropes, a car and a counterweight hung from the opposite ends of the ropes, vertical holes in the top of the car and the counterweight, the holes being of sufficient size to receive the thimble-rods 45 and allow the rods to be freely turned and moved therein from side to side, collars around the rods and entered in the holes at the bottom thereof, said collars serving to center the rods in the holes, springs beneath 50 the collars and sleeved on the rods, and means to keep the springs in place and allow them and the collars to turn with the thimble-rods, when the leads of the ropes twist, the springs serving to equalize the 55 effective length of the leads of the ropes and minimize the wear of the ropes and the grooves in the driving sheave.

8. In a traction elevator, the combination of a grooved driving sheave, hoisting ropes 60 in the grooves, the car and counterweight, hung from opposite ends of the ropes, the top weight of the counterweight being cored with staggered openings, set in lines drawn at an angle to the major axis of the top 65 weight, thimble-rods, fast to the ends of the ropes, and passed through the openings, springs on the rods and nuts holding the springs between them and the counterweight, whereby a minimum length of leads is obtained and the effective length of them 70 equalized.

In testimony whereof, I have signed my name to this specification:

DAVID L. LINDQUIST.
